METHOD OF PREPARING PREWELTED
UPPERS

Joseph Fausse, Melrose Highlands, Mass., assignor to United Shoe Machinery Corporation, Paterson, N. J., a corporation of New Jersey

Application April 16, 1936, Serial No. 74,725

8 Claims. (Cl. 12—146)

This invention relates to methods of preparing pre-welted uppers, that is, uppers in the manufacture of which a welt is stitched to the everlasting margin before the upper is lasted.

5 Pre-welted uppers are usually lasted by means engaging the upper between the upper-attaching face of the welt and the outer face of the everlasting margin, said region being commonly referred to as the welt crease. For example, it is 10 a usual practice to last pre-welted uppers in bed lasting machines by means of lasting wipers constructed and arranged to engage the upper within the welt crease. Pre-welted uppers usually come to the lasting operation with the welt held close 15 to the upper throughout its entire width by the seam uniting the welt and upper and the lasting machine operator is required to bend the welt away from the upper before he can last the shoe. This is a difficult and tedious operation and 20 greatly retards the production of the lasting machine operator.

It is an object of the present invention to prepare pre-welted uppers for the operations subsequent to the welt-stitching operation, and particularly for the lasting operation, thereby to 25 make it unnecessary for the lasting machine operator to prepare the welted margin of the upper for the lasting operation. With this in view the invention, in one aspect thereof, comprises stitching a welt to the everlasting margin of an upper which has not been mounted on a last, and thereafter, before operating on the everlasting margin to arrange the welt for the reception of an outsole, progressively bending the welt outwardly from the everlasting margin of the upper and simultaneously applying pressure to the welt thereby to cause its outer margin to be longer 30 than its inner margin at the outwardly curved portions of the upper.

40 In accordance with a usual method of manufacturing pre-welted shoes the upper is secured in lasted position by adhesively attaching a sole to the welt while the upper is supported in the lasting machine. In order to prepare the welt 45 for the cement attachment of a sole thereto it is proposed to apply adhesive to the sole-attaching face of the welt during the upper-preparing operation and accordingly the present invention, in another aspect thereof, comprises applying adhesive to the sole-attaching face of the welt while the welt is being bent outwardly from the everlasting margin of the upper.

50 The various aspects of the invention will appear more fully from the following description when read in connection with the accompanying

drawing and will be pointed out in the appended claims.

Referring to the drawing, a pre-welted upper 2 which has not been mounted on a last is arranged in inverted position for operation thereon by a 5 machine herein illustrated as a machine for applying cement to upper parts such, for example, as the sole-attaching face of the welt of a pre-welted upper. The upper is supported by the operator and the welt is positioned between a supporting roll 4 which, as herein illustrated, engages the upper-attaching face of the welt and the adjacent surface of the upper, and a roll 6 which is illustrated in engagement with the sole-attaching face of the welt. The roll 6 is knurled 10 for the reception of cement which is delivered thereto from a trough 8 by a roll 10 which dips into the cement in said trough and a roll 12 between the rolls 6 and 10. The supporting roll 4 is mounted on an arm 13 which swings to move 20 the roll 4 toward the cement-applying roll 6.

In practicing the method of the present invention the welt 14 of the pre-welted upper 2 is positioned with its upper-attaching face against the peripheral face of the supporting roll 4 and 25 the adjacent surface of the upper against one side of said roll. The roll 4 is then moved upwardly to press the sole-attaching face of the welt against the cement-applying roll 6 whereupon 30 said rolls are rotated to transfer the point of operation progressively about the welted margin of the upper. As the point of operation progresses about the ends of the upper the welt-engaging rolls cause the welt to project outwardly from the margin of the upper and in so doing they cause 35 the outer margin of the welt to lengthen or stretch somewhat and a substantial amount of the lengthening of the outer margin of the welt by the action of the rolls is retained by the welt. Thus it will be seen that the welt is permanently 40 shaped to cause it to project outwardly from the margin of the upper. The operation of the welt-engaging rolls also operates to bend the welt at the sides of the upper away from the margin 45 of the upper and a considerable amount of the bend is retained by the welt. Thus it will be seen that the operation of the illustrated machine on the welted margin of the upper causes the welt throughout its entire extent to project outwardly 50 from the margin of the upper and provides a space between the welt and the upper within which lasting means, for example, the wipers of a bed lasting machine, may engage without the requirement of a preliminary operation on the 55

welted margin of the upper by the lasting machine operator.

Having thus described my invention, what I claim as new and desire to secure by Letters Patent of the United States is:

1. That method of preparing pre-welted uppers which consists in stitching a welt to the everlasting margin of an upper which has not been mounted on a last and thereafter, before operating on the welted margin to arrange the welt for the reception of an outsole, progressively bending the welt outwardly from the everlasting margin of the upper and simultaneously applying pressure to the welt thereby to cause its outer margin to be longer than its inner margin at the outwardly curved portions of the upper.

2. That method of preparing pre-welted uppers which consists in stitching a welt to the everlasting margin of an upper which has not been mounted on a last and thereafter, before operating on the everlasting margin to arrange the welt for the reception of an outsole, progressively bending the welt outwardly from the everlasting margin of the upper and simultaneously applying adhesive to the sole-attaching face of the welt.

3. That method of preparing a pre-welted upper before the upper is mounted on a last which consists in applying rolling pressure simultaneously to the outer surface of the welted margin of the upper and the upper-attaching face of the welt thereby to cause the welt to project outwardly from the upper.

4. That method of preparing a pre-welted upper which consists in progressively operating on the welt before the upper is lasted by means including a roll constructed and arranged to engage and press against the welt thereby to cause the outer margin of the welt at the curved portions of the upper to be longer than the corresponding portions of the inner margin of the welt.

5. That method of preparing a pre-welted upper before the upper is mounted on a last which consists in progressively operating on the welt by means of coacting rolls constructed and arranged to engage, respectively, the upper-attaching face and the sole-attaching face of the welt and to bend the welt outwardly from the margin of the upper.

6. That method of preparing a pre-welted upper which consists in progressively operating on the welt by means of rolls constructed and arranged to engage, respectively, the upper-attaching face and the sole-attaching face of the welt and to bend the welt outwardly from the margin of the upper, and simultaneously applying adhesive to the sole-attaching face of the welt.

7. That method of preparing a pre-welted upper before the upper is lasted for the attachment of a sole to the welt which comprises progressively operating on the welt by means of rolls constructed and arranged to engage, respectively, the upper-attaching face and the sole-attaching face of the welt, and moving the rolls toward each other to press the welt therebetween and to stretch the outer margin of the welt at the ends of the upper thereby to cause the welt at the ends of the upper to project outwardly from the margin of the upper.

8. That method of preparing a pre-welted upper for the attachment of a sole to the welt which comprises progressively operating on the welt by means of rolls constructed and arranged to engage, respectively, the upper-attaching face and the sole-attaching face of the welt, moving the rolls toward each other to press the welt therebetween and to stretch the outer margin of the welt at the ends of the upper thereby to cause the welt at the ends of the upper to project outwardly from the margin of the upper, and applying cement to the sole-attaching face of the welt by means of the roll which engages said face.

JOSEPH FAUSSE.
